UNITED STATES PATENT OFFICE.

ROBERT BERTRAM GREY, OF LONDON, ENGLAND.

MIXING APPARATUS.

1,409,542.

Specification of Letters Patent. Patented Mar. 14, 1922.

Application filed July 19, 1920. Serial No. 397,254.

To all whom it may concern:

Be it known that I, ROBERT BERTRAM GREY, a subject of the King of the United Kingdom of Great Britain and Ireland, and 5 residing at London, England, have invented a certain new and useful Improvement in or Relating to Mixing Apparatus, of which the following is a specification.

This invention relates to improvements in 10 and connected with mixing apparatus of the vortex type.

In mechanical agitators for mixing liquids, semi-liquids and liquids and solids, of 15 the type where a blade or blades is or are rotated on a vertical shaft and baffle plates are arranged down the sides of the mixing tank, a large amount of power is wasted in overcoming the resistance offered by the 20 baffle plates to the natural rotation of the liquid induced by the revolving blades.

In my invention these side baffles are dispensed with and a plurality of independently adjustable breakers or baffles capable of adjustment to individually different 25 depths of immersion in the contents of the mixing tank are arranged on the top of the vessel.

This improved arrangement of breakers or baffles greatly reduces the power required 30 to operate the mixing apparatus and greatly increases the efficiency of the mixing effect.

The invention is illustrated in the accompanying drawing in which Fig. 1 is a vertical section and Fig. 2 a plan of a mixing 35 apparatus fitted with the improved arrangement of breakers or baffles.

As shown, the breakers or baffles (three are shown) each consists of a flat plate A preferably wider at one end than at the other, said plates being supported by rods B passing through the cover C of the mixing apparatus and connected at their upper ends to form a handle D. The rods B are perforated at intervals throughout their length 40 as at E for the insertion of locking-pins F adapted to bear on upstanding lugs G on the cover C so as to permit of supporting each baffle at various heights within the contents of the tank T.

50 In operating the mixing apparatus the baffles A are partially immersed in the contents of the tank. The propeller H is rotated and sets up a vortex in the contents, the propeller being mounted on a vertical shaft I fitted with a bevel gear wheel J meshing with a bevel wheel K secured on a

shaft L on which are fitted fast and loose pulleys MN. The fast and loose pulleys are embraced by a belt (not shown) which is connected to a suitable prime mover. The 60 action of the breakers or baffles A breaks up the surface tension of the contents whereby continuous streams are returned into the vortex and an agitating effect is set up.

By reference to Fig. 2 it will be understood that the baffles, which are adjustably supported by the cover of the tank, are widely separated from the sides of the tank, instead of being closely adjacent to the sides of the tank as heretofore; so that the waste 70 of power in the operation of the mixer, hereinbefore referred to, is avoided by the present improved arrangement of the baffle plates.

It has been found by experiment that by 75 adjustment to different depths of the various baffles the agitating or mixing effect of the whole device can be increased. The depth of immersion is varied according to the difference in specific gravities of the materials 80 under treatment.

The tank T is preferably provided with an inverted conical bottom and the propeller or stirrer H, which is attached to the lower end of the vertical shaft I, is arranged to 85 rotate horizontally within the chamber of the pan afforded by said conical bottom, so that an outward and upward flow of the liquid which is being agitated is induced when said propeller or stirrer is in operation. This flow of the liquid is intercepted 90 by the baffles A in the upper part of the mixing chamber, so that the said baffles cooperate with the said rotating propeller or stirrer in the mixing operation. These baffles A have outwardly and upwardly inclined lower edges to induce an inward and downward flow of the liquid to assist in the outward and upward flow of the liquid induced by rotating the propeller or stirrer. 100

Although I have shown an arrangement for manual independent adjustment of the baffles it is clear that the baffles may be adjusted independently of one another by mechanical means.

I claim:

1. In a mixing apparatus, the combination with a tank provided with a cover, of baffles adjustably supported by said cover and depending therefrom into the upper 110 part of the chamber of said tank, said baffles being widely separated from the sides of

the tank and consisting of flat plates the lower edges of which are above the vertical middle part of the said tank.

2. In a mixing apparatus, the combination 5 with a tank provided with a cover, of baffles adjustably supported by said cover and depending therefrom into the upper part of the chamber of said tank, said baffles being widely separated from the sides of the tank 10 and consisting of flat plates which are so arranged as to be widely separated from the walls of the tank, said plates having outwardly and upwardly inclined lower edges.
- 15 3. In a mixing apparatus, the combination with a tank, of a cover on said tank, a propeller rotatable in said tank, a plurality of baffles in said tank, said baffles presenting plane surfaces, pairs of supporting rods connected to said baffles and extending through said cover, said rods being each provided with a series of spaced perforations, a han-

dle connecting the rods of each pair above said cover, and locking pins adapted for insertion in selected perforations so as to sustain said baffles at selected elevations. 25

4. In a mixing apparatus, the combination with a tank provided with a cover and having an inverted conical bottom, of a vertical shaft, a horizontally arranged stirrer attached to the bottom of said shaft and rotating horizontally within the chamber of said bottom, and baffles adjustably suspended from said cover and disposed in the upper part of the chamber of the said tank 30 and with which baffles said stirrer cooperates.

In testimony whereof I have signed my name to this specification in the presence of two subscribing witnesses.

ROBERT BERTRAM GREY.
